UNITED STATES PATENT OFFICE.

ARTHUR G. WITT AND SCOTT BRASHEAR, OF SOMERSET, PENNSYLVANIA.

DESIGN FOR A DISPLAY-STAND.

49,001.

Specification for Design.

Patented May 2, 1916.

Application filed January 28, 1916. Serial No. 74,877. Term of patent 7 years.

To all whom it may concern:

Be it known that we, ARTHUR G. WITT and SCOTT BRASHEAR, citizens of the United States of America, residing at Somerset, county of Somerset, and State of Pennsylvania, have invented a new, original, and ornamental Design for a Display-Stand, of which the following is a specification, reference being had to the accompanying drawing, forming part thereof, which illustrates the display-stand in perspective.

The design is embodied in a container or holder of peculiar form for fruits and vegetables and other articles, and a stand having a circular top which fits into a circular cavity in the base of the container and is provided with vertical legs.

We claim:

The ornamental design for a display stand, as shown and described.

ARTHUR G. WITT.
SCOTT BRASHEAR.
